UNITED STATES PATENT OFFICE.

ALBERT MAESCHER, OF ST. LOUIS, MISSOURI, ASSIGNOR OF ONE-HALF TO HAROLD J. WRAPE, OF ST. LOUIS, MISSOURI.

IRONING MACHINE.

Application filed October 8, 1924. Serial No. 742,297.

This invention relates to ironing machines, and more particularly to such clothes ironing machines as may be used for domestic ironing operations.

5 One of the objects of this invention is to provide improved mechanism for operating an ironing machine of this type.

Another object of this invention is to provide an improved construction of the table 10 permitting easier handling thereof and removal when required.

Another object of this invention is to provide improved means for taking up the strain due to the pressure between the table 15 and the roll.

Further objects will appear from the detail description taken in connection with the accompanying drawings, in which:

Figure 1 is a perspective view showing an 20 ironing machine embodying this invention;

Figure 2 is a fragmentary plan view illustrating the reversing mechanism;

Figure 3 is an end view of Figure 1 with parts shown in section;

25 Figure 4 is a section on line 4-4, Figure 3;

Figure 5 is a section taken about on line 5-5 Figure 6 and illustrating the table support;

30 Figure 6 is a sectional view through the table support;

Figures 7, 8 and 9 show different forms of table boards;

Figure 10 is an end view of the roll with 35 the gear removed and showing the mounting of the hood;

Figure 11 is a detail of Figure 10, and

Figure 12 is a view of the braking mechanism taken on line 12-12, Figure 1.

40 Referring to the accompanying drawings the machine is supported generally by a pair of end frames 1 which may be iron castings or similar structures. These frames are connected by a series of cross-bars 2

45 which serve to space the end frames and also as supports for certain parts of the mechanism. Mounted on the lower pair of cross-bars 2 is a bracket 3 on which is supported an up-right column 4, within which is

50 mounted the support for the ironing table 5 as will be hereinafter more fully described. Mounted between the side frames 1 is an ironing roll suitably heated and provided with mechanism for causing the same to

travel forwardly across the ironing table 5 55 and then return to its rearward position.

Referring now more particularly to Figures 2, 3 and 4, each end frame 1 is provided with a cross-member 7 upon which is fixed a rack 8. Mounted to roll on the rack 8 is 60

a gear 9. There is a pair of gears 9, each rolling on a rack 8 on one of the end frames 1. These gears carry between them and

fixed thereto a shaft 10 which also carries between the gears the ironing roll 6. The 65

shaft 10 is hollow and may be provided with a suitable connection for attachment to a gas supply or similar heat supply. The

shaft 10 may also be provided within the roll 6 with suitable jets or burners adapted 70 to heat the roll. The heating connections are well understood in the art and, therefore,

need no detail description here. Mounted in bearings 11 in one of the end frames 1 is an elongated worm or screw 12. This 75

screw extends parallel with the rack 8 and engages the teeth of the gear 9 so as to provide means for driving said gear in rotation. The gear 9 on this side is preferably a spiral

or skew gear in order to mesh with the worm 80 12. The shank of the screw 12 carries at its rearward end a pulley or sheave 13 adapted

to be driven by a belt 14 from the driving mechanism which will presently be described. When the screw 12 is rotated, it 85

will act as a worm engaging the gear 9 so as to drive the same in rotation. Such rotation will, of course, on account of the engagement with the rack 8, which may also

have spiral teeth, drive the gear longitudinally along the end frame 1 so as to move the roll 6 across the table 5.

Since the table 5 is arranged, as will hereinafter be more fully described, to bear against the roll under pressure, means are 95 provided for taking up the resulting strain on the roll 6 so as to relieve the screw 12 thereof. These means are illustrated in Figures 3 and 4. A pair of longitudinal rails

15 extend across each end member 1 above 100 and parallel with the rack 8. The shaft 10 passes between said rails and carries loosely mounted thereon a flanged roller 16 engag-

ing the rails 15. These rails form guides for the shaft 10 and the roll 6 to limit endwise 105 play of the roll and take up the pressure of the table 5 or the weight of the roll and its connected parts.

The belt 14 passes around a sheave or pulley 17 on a shaft 18 journalled in a bracket 19 suitably mounted on the lower part of the frame. The shaft 18 is mounted 5 for a limited axial movement in its bearings and is equipped at one end thereof with a grooved collar 20 adapted for engagement by pins 21 in the forked end of a lever 22 secured to a pivot pin 23, which is pivoted in 10 on a sub-bracket 24 of the bracket 19. The lever 22 may be operated to slide the shaft 18 in its bearings as will be described later.

The shaft 18 carries a pair of beveled friction discs 25 adapted to engage the 15 corresponding beveled friction disc 26 carried by a shaft 27 driven by a suitable driving motor 28. Both of the discs 25 are fixed to the shaft 18 so that by shifting said shaft axially, either of the discs 25 may be 20 brought into engagement with the disc 26. Thus the shaft 18 may be rotated in opposite directions by bringing one or the other of the discs 25 into engagement with the disc 26. This, therefore, provides a reversible 25 driving mechanism for operating the roll.

Suitably pivoted on the cross-bar 29 extending between the end frames 1 is a treadle 30. This treadle is fixed to the bar 29 so as to rotate the same when depressed. The 30 bar 29 also carries a crank-arm 31 connected by a link 32 with the lower end of the lever 22. A spring 33 is also connected at one end with the lower end of the lever 22 and at its other end to the frame as illustrated 35 in Figure 3. This spring is adjusted in tension so as to raise the treadle 30 when released by the operator. It will be clear that when the treadle 30 is depressed, the bar 29 will be rotated so as to swing the 40 arm 31 to the right, Figure 3, thereby operating the lever 22 so as to move the shaft 18 to the left, Figure 3. This will bring one of the discs 25 into engagement with the disc 26 so as to operate the screw 12 in such 45 a direction as to drive the gear 9 forwardly along the rack 8 so as to move the roll 6 forwardly across the table 5. As soon as the treadle 30 is released, the spring 33 will raise the same and the roll will be automatically 50 stopped and retracted as will now be more fully described. The treadle is thus self-returning so that it may be manipulated by simple pressure and release.

Pivoted at 34 on one of the end frames 55 1 is an arm or lever 35 connected by means of a vertical link 36 with an arm 37 fixed to the shaft forming the pivot 23. Both the arm 37 and the lever 22 are fixed to this shaft 23. It will be clear, therefore, 60 that when the arm 35 is rocked about its pivot, the link 36 will rock the arm 37 and, therefore, the lever 22 about its pivot so as to shift the shaft 18 to bring one of the discs 25 into or out of engagement with the disc 26. The arm 35 is provided at its forward

end with a block or facing 38 which may be of steel or other suitable material adapted to engage a tappet 39 mounted on the gear 9. The gear 9 and the rack 8 are so proportioned that the gear will make one complete revolution in traveling from its rearward position to its forward position as shown in Figure 3. When the gear reaches the forward end of its travel, therefore, the tappet 39 will strike the block 38 depressing the forward end of the lever 35 so as to lift the link 36, thereby rotating the shaft 23 so as to operate the lever 22 to reverse the drive. This device, therefore, limits the forward travel of the roll across the table 80 and immediately reverses the travel, moving the roll back again across the table to its original position. As the gear reaches the rearward limit of its travel, the tappet 39 strikes a facing 40 similar to the facing 38 85 but on the opposite end of the lever 35. The facing 40, however, is not so high as the facing 38 and is adjusted so that the movement of the arm 35 consequent upon the engagement of the tappet with the facing 40 90 is just enough to cause the shaft 18 to be shifted to neutral position with both of the discs 25 out of engagement with the disc 26. With the discs in this position, however, the drive is cut off and the travel of the roll 95 will stop. It will be clear, therefore, that when the operator depresses the treadle 30 the roll will travel forwardly across the table to the forward limit of its travel where it will be automatically reversed to travel back again to its original position where it will stop. The operation of the lever 22 in stopping the roll will at the same time raise the treadle 30 to its original position. The spring 33 operates the reversing mechanism 100 so as to retract the roll. The roll, however, at the end of its return travel operates the lever 35 so as to throw the reversing mechanism into neutral and stop the machine. The operator must be guided in the manipulation of the treadle 30 by the action of the machine. When the treadle is depressed the roll starts forward. At the limit of its forward travel it operates the lever 35 to shift the reversing mechanism and retract the roll, at the same time raising the treadle 30. At this point the operator will remove 110 his pressure from the treadle. The roll now travels backward until the tappet 39 engages the plate 40 and operates the lever 35 to shift the reversing mechanism to neutral. Thus the roll always stops in retracted position clear of the table. 115

In order to absorb the momentum of the roll and check the return movement thereof, a brake is provided as illustrated in Figure 12. A pin 81 is fixed to one of the gears 9 in a position to engage a pivoted brake member 82 at the completion of the return stroke of the roll. The brake member 82 is pivoted 120

125

at 83 on one of the end frames 1, and is yieldingly tensioned by a spring 84 attached to the end of the member 82 and anchored to the frame 1. This provides a yielding 6 stop to check the return movement (indicated by the arrow in Figure 12) of the roll, and prevent the same from striking against the frame.

Referring now more particularly to Figures 5 to 9 inclusive, the bracket 3 is carried by the lower cross-bars 2 and in its turn carries together with the end bracket 1 the base 41 upon which the motor 28 and the bracket 19 are mounted. This bracket 3 15 also supports the up-right column 4 supporting the table 5 as previously pointed out. The column 4 may be in the form of a tube within which is mounted the shank of a carrier 42, the lower end of which rests 20 upon a spring 43 bearing on the head 44 of a stem 45 suitably guided by the column 4 and passing through the bracket 3, being pivoted below said bracket at 46 to a lever 47. The lever 47 is pivoted at 48 to a down- 25 ward extension 49 of the bracket 3. The lever 47 extends forwardly and is equipped at its end with a pedal 50 pivoted at 51 to the lever 47 and held by a spring 52 against a stop pin 53 on the lever 47. The pedal 50 30 is provided with a lip 54 adapted to take over a lug 55 on the bracket 3 to hold the lever 47 in operative position. The rear- 35 ward end of the lever 47 bends downwardly and is equipped with a laterally projecting pin 56.

The upward travel of the carrier 42 is limited by a stop 810 fixed in the column 4 and engaging a head 820 on the carrier. This stop 810 locates the carrier in its upper- 40 most position in the column but permits depression thereof against the spring 43. The carrier 42 has a pin 57 engaging a slot 58 in the column 4 so as to retain the carrier against rotation. The upper end of the car- 45 rier 42 is provided with a slot 59 adapted to receive a pin 60 carried by a socket 61 attached to a board or plate forming the body of the table 5. A number of such boards or plates may be provided of different shapes 50 as illustrated in Figures 7, 8 and 9. Each board is provided with a socket 61 adapted to fit on the carrier 42. Each board may also be suitably padded and covered as is the usual practice for ironing boards. It 55 will be noted that the table 5 is thus yieldingly mounted so that when the roll passes thereover, it will be depressed against the spring 43 which provides a suitable pressure for the ironing operation.

It happens occasionally that during the ironing operation an accident, such as the blowing of a fuse, may stop the operation of the roll. If the roll should stop when in engagement with the table, the work will 60 be injured by continued exposure to the heat

of the roll. When such an emergency takes place, the operator by depressing the pedal 50 may cause the stem 45 to be lowered, thereby allowing the carrier 42 to drop in the column 4 to the limit of its movement. 70 This carries the table 5 downwardly so as to move the table out of engagement with the roll. In order to restore the table to operative position after the same has been depressed, a lever 63 is provided. This lever 75 is pivoted at 64 to a downward extension 65 on the bracket 3 and extends forwardly alongside of the lever 47 as shown in Figure 5 and is provided with a pedal 66 adjacent the pedal 50. This lever is held in raised 80 position by a spring 67 and is provided with an upwardly bent portion 68 to provide a stop engaging the bracket 3. The pin 56 on the lever 47 extends under the lever 63. When the lever 47 is dropped so as to lower 85 the table, the pin 56 will be raised into engagement with the lever 63. When in this position depression of the pedal 66 will move the lever 63 downwardly, thereby depressing the pin 56 and rocking the lever 47 back to 90 its operative position. When the lever 47 reaches its upward position, the catch 54 will snap over the lug 55 and retain the lever in that position. The pedal 66 thus provides means for restoring the table to 95 operative position after it has been depressed.

A guard 69 may be provided for the roll 6. This guard is designed to protect the roll and the operator and may be constructed of sheet metal or other suitable material and 100 may be provided with a series of perforations 70 to permit the escape of heated air thereby cooling the guard. The guard is open at the bottom so as to permit the roll 105 to engage the table. The guard 69 is loosely mounted on a pair of cross-bars 71 carried by a pair of brackets 72 hinged on the shaft 10. The guard 69 being loosely laid on the rods 71 may be removed at any time for 110 inspection or cleaning of the roll. In order to maintain the guard in up-right position the brackets 72 may be provided with rollers 73 adapted to take under an out-turned lip 74 formed on a guard 75 which covers and 115 protects the gears 9 in their travel along the frame.

In the normal operation of this machine the roll is heated by gas jets or other suitable means, such as electric heaters. The table 5 is held normally in raised position 120 with the spring 43 untensioned. The work is laid upon the table 5 in the desired position and the treadle 30 is then depressed. This causes the roll to move forwardly across the table to the forward end of the frames and then rearwardly to its original position where it stops. The work is ironed by the roll in its passage over the table. The work may then be shifted so as to bring 125 another portion thereof on the table and the 130

operation is repeated. The roll may be moved through only part of its forward travel and then reversed or retracted. A back-and-forth movement through a short distance may also be produced by proper manipulation of the treadle. This procedure is continued until the piece is completely ironed.

It will be noted that the roll is driven by gearing which carries the same across the table, first in a forward and then in a rearward direction. A reversible driving mechanism drives this gearing and is connected to be operated by the pivoted lever 35. This lever extends along the travel of the gearing and is engaged by the same at the ends of its travel and at opposite ends of the lever. At the forward end, the operation is to reverse the drive so as to reverse the travel of the roll and at its rearward end the roll is stopped.

The table is arranged to maintain a uniform pressure of the work against the roll and the rails 15 provide for taking up this pressure on the roll. It will be seen that the roll is left in a position back of the table so as to clear the same: accordingly the table may at that time be readily removed and replaced with another one of different shape or size. This table may also be dropped or raised at any time by dropping and raising its support through the medium of the treadles 50 and 66. A pan 80 carried by the ends 1 provides a receptacle below the roll for the clothes, and more especially the loose ends thereof.

It will be seen, therefore, that this invention provides a simple machine for carrying out ordinary domestic ironing operations and one which is convenient to handle and capable of doing rapid work. The same is also provided with safety devices to prevent damage in the case of emergencies.

It will be also noted that the roll 6 is of less diameter than the gears 9 which give the roll its linear movement. Consequently the rotary movement of the periphery of the roll will be less than the linear movement thereof. This provides that the roll will have a sliding movement forwardly over the table and with respect to the clothes, a movement which produces an ironing and smoothing effect similar to that of the ordinary sad iron. This movement is effective, for instance, in ironing collars and similar articles, to produce the much desired sheen on the ironed surface without too pronounced a gloss such as is usually produced by a roll having only rotary movement without linear movement.

It is obvious that various changes may be made in details of construction without departing from the spirit of this invention; it is, therefore, to be understood that this

invention is not to be limited to the specific details shown and described.

Having thus described the invention, what is claimed is:

1. A clothes ironing machine, comprising, a frame, an oblong table mounted in said frame, a heated roll mounted in said frame and along said table and guided for movement transversely over said table, means for moving said roll over said table, and means actuated by a part rotating with said roller for reversing said movement.

2. A clothes ironing machine, comprising, a frame, an oblong table mounted in said frame, a heated roll mounted in said frame and along said table and guided for movement transversely over said table, gears on said roll, racks engaging said gears and adapted to maintain the alinement of said roll, and means engaging said gears adapted to drive said roll back and forth.

3. A clothes ironing machine, comprising, a table, a heated roll adapted to travel across said table and a ventilated guard for said roll adapted to move therewith and positioned so as to be removed from influence of the means for heating said roll.

4. A clothes ironing machine, comprising, a table, a heated roll adapted to travel across said table and a ventilated guard for and carried by said roll and positioned so as to be removed from influence of the means for heating said roll.

5. An ironing machine, comprising a heated roll, a table, gearing adapted to move said roll across said table, reversing mechanism for said gearing, and a lever connected to said mechanism to control the same, said lever being engagable by a part rotating with said roll at one end of the travel thereof to operate said mechanism to reverse said roll and at the other end thereof to disconnect said mechanism to stop said roll.

6. An ironing machine, comprising, a heated roll, a table, driving means connected with said roll and mounted for longitudinal travel to move said roll across said table, a pivoted arm extending along the travel of said driving means, a tappet on said driving means adapted to engage said arm at the end of said travel, and means connected with said arm for reversing said travel.

7. An ironing machine, comprising, a heated roll, a table, gearing connected with said roll and mounted for longitudinal travel to move said roll across said table, a pivoted arm extending along the travel of said gearing, reversible and disconnectible driving mechanism connected with said arm, a tappet on said gearing adapted to engage said arm at one end thereof and move the same to reverse said mechanism and at the other end thereof to disconnect said mechanism.

8. In a clothes ironing machine having a heated roll mounted on a shaft, a hood for the roll supported on the shaft and means for guiding said hood to maintain the same in upright position.
9. In a clothes ironing machine having a heated roll mounted on a shaft, a hood for the roll, means for supporting said hood on the shaft, and a guiding rail cooperating with and adapted to keep said hood in upright position.
10. In a clothes ironing machine having a heated roll mounted on a shaft, a hood for the roll, a bracket on said shaft for supporting said hood on the shaft, a guiding rail, and means on said bracket engaging said rail to keep said hood in upright position.
11. A clothes ironing machine, comprising, a frame, a table, a roll guided for movement forward and backward on said frame and over said table, a stop moving with said roll, and a yielding brake positioned to be frictionally engaged by said stop to check the return movement of said roll.
12. A clothes ironing machine, comprising, a frame, a table, a roll guided for movement forward and back on said frame and over said table, a stop moving with said roll, and a spring controlled arm positioned to be frictionally engaged by said stop to check the return movement of said roll.

In testimony whereof I affix my signature
this 29th day of August, 1924.

ALBERT MAESCHER.
